Primary Examiner—Mark A Goodwin*(74) Attorney, Agent, or Firm*—Duane Morris LLP**CLAIM**

The ornamental design for a package of containers, as shown and described.

DESCRIPTION

FIG. 1 is a top perspective view of the package of containers showing our new design;

FIG. 2 is a top view of the package of containers;

FIG. 3 is a bottom view of the package of containers;

FIG. 4 is a side view of the package of containers; and,

FIG. 5 is a front view of the package of containers, the rear view being a mirror image thereof.
